UNITED STATES PATENT OFFICE.

JOSEPH D. SELF, OF WAYNESVILLE, NORTH CAROLINA.

CHANGEABLE SIGN.

Application filed March 19, 1928. Serial No. 262,715.

This invention relates to a changeable sign designed primarily for use on public vehicles, one of the objects being to provide means whereby, during the travel of a vehicle over any route, a series of signs arranged on an elongated web, will be successively displayed to the occupants of the vehicle, each sign being held stationary for a predetermined time before the display is changed.

A further object is to provide a device of this character which is simple and compact in construction, can be installed readily, and can be reset readily after all of the signs have been displayed.

With the foregoing and other objects in view which will appear as the description proceeds the invention resides in the combination and arrangement of parts and in the details of construction hereinafter described and claimed, it being understood that changes in the precise embodiment of the invention may be made within the scope of what is claimed without departing from the spirit of the invention.

In the accompanying drawings the preferred form of the invention has been shown.

In said drawings,

Figure 1 is a perspective view of a portion of the interior of a public vehicle showing in position a changeable sign such as constitutes the present invention, the means for actuating the sign being disclosed more or less in diagram.

Figure 2 is an enlarged front elevation of a changeable sign.

Figure 3 is an elevation of one side thereof.

Figure 4 is an enlarged section on line 4-4, Figure 2.

Figure 5 is a section on line 5-5, Figure 4, the middle portion of the structure being broken away.

Figure 6 is a section through the shiftable gear and its operating means.

Figure 7 is a detail view of a portion of the web.

Referring to the figures by characters of reference 1 designates a box-like casing the front face of which can be formed of a door 2 hingedly mounted as at 3 and adapted to be fastened in closed position by any suitable means. This door has an opening 4 through which the changeable sign or web is exposed.

A bearing plate 5 is mounted in the hous-

ing 1 adjacent one side and has bearings 6 in which is journalled a shaft 7 provided with a screw thread or worm 8. This shaft is adapted to be coupled in any suitable manner to a flexible shaft 9 which may be arranged in any suitable location within the vehicle V in which the changeable sign is located, the lower portion of this flexible shaft being connected by suitable gearing 10 to the hub portion H of one of the wheels of the vehicle or to any other rotating part. Thus as the vehicle travels forwardly motion will be transmitted through the gears 10 to the flexible shaft 9 and the worm shaft 7 will therefore be rotated continuously as the vehicle travels.

The worm 8 meshes with a worm gear 11 carried by a short shaft 12 journalled in one side of the housing 1 and in the bearing plate 5, as shown particularly in Figure 5. This shaft has a segmental gear 13 which rotates therewith.

A shaft 14 is journalled in one side of the housing 1 and in the bearing plate 5 and mounted for rotation with this shaft is a spool 15 having a tubular core 16 through which the shaft extends. One end portion of the shaft is screw threaded as shown at 17 so as to engage corresponding threads within the core and attached to one end of the shaft is a crank 18 or the like whereby the shaft can be rotated in one direction for the purpose of winding a web 19 about the spool. Obviously by rotating the shaft 14 in the opposite direction, said shaft can be unscrewed from the core 16 and slid longitudinally out of the core so as to reach the spool. During the winding operation, however, the thread 17 can screw into the core 16 and thus prevent the parts from becoming separated.

One end of the elongated web 19 is attached to the core of the spool 15 while the other end thereof is attached to the core 20 of a spool 21. The ends of the core 20 are journalled in one side of the housing 1 and in the plate 5 respectively, that end journalled in plate 5 being formed with an angular recess 22. This recess is adapted to receive the angular end 23 of a spindle 24 slidable in the recess and extending from one side of the center of a gear 26. A circular boss 27 is provided on the other side of the gear and has an annular flange 28. From the center of this boss extends a spindle 29 on which the sleeve 30 is mount-

ed to rotate. This sleeve has a collar 31 at one end which embraces the boss and engages back of the flange 28 so that when the sleeve is pulled longitudinally the gear 26 will likewise be moved therewith. However the sleeve can be rotated without rotating the gear and its spindle.

One end portion of the sleeve 30 extends through the side of the housing 1 and has a knob 32 whereby it can be pulled and rotated. A longitudinal slot 33 is formed in the sleeve and has a lateral extension 34. A pin 35 is extended into the slot, this pin being attached to the side of the housing 1. A spring 36 is mounted on the sleeve and bears against the side of the housing and against the collar 31, thus to hold the spindle 24 normally seated in the recess 22 and the gear 26 normally positioned where it will be engaged by the gear 13.

Secured to the inner side of one of the walls of the housing is a spring 37 having small nodes 38 each of which is adapted to be seated within any one of a series of recesses 39 formed in one of the spools. A screw 40 is mounted in the wall of the housing and bears against the middle portion of the spring for bearing the tension thereof. This spring and its projecting nodes constitute means for preventing the spools from rotating freely.

The signs to be displayed are painted or otherwise formed on the elongated web 19, each sign being so proportioned as to have all portions thereof appear within the opening in the door 2 while the web is at rest. To compensate for variations in the diameter of the roll of web, the signs are spaced different distances from each other, this distance gradually increasing from one end of the web to the other.

By arranging the signs in this manner no compensating mechanism is necessary because as the size of the roll of web increases in diameter and the speed of the web is correspondingly increased, the distance between the signs is likewise increased. Each rotation of gear 13 is adapted to produce one complete rotation of the gear 26 and spool 21. During each rotation of the spool one sign will be brought to position back of the opening 4 where it will be exposed to view.

As the vehicle travels forwardly motion will be transmitted through the flexible shaft to the worm 8 and thence to the gears 11 and 13. As before explained, each time gear 13 rotates the spool 21 is given a complete rotation, winding a portion of the web thereon so that the web will pull on the lower spool 15 and cause it to rotate. Neither of the spools can spin, however, because of the brake provided in the form of the spring 37. When the vehicle is to be backed, the apparatus can be uncoupled from the vehicle wheel by any suitable means pro-

vided for that purpose or, if preferred, the sleeve 30 can be pulled outwardly as shown by broken lines in Figure 6 and given a partial rotation so as to seat the pin 35 in the slot extension 34. This will pull the gear 26 out of mesh with the gear 13 where it will be held. This position of the parts is also set up when it is desired to reset the web by winding it on the spool 15, the crank 18 being employed for this purpose. This actuation of the crank causes the shaft 14 to bind tightly in the core 16 at the threaded portion 17 so as to rotate the spool 15 as long as the crank is rotated in one direction.

Obviously, by providing the mechanism so described, each sign will be brought to position back of the opening 4 while the gears 13 and 26 are in mesh and, when gear 13 moves out of mesh with gear 26 the sign will be left stationary until the gears are again brought into mesh and another sign brought to exposed position.

By opening the door 2 the two spools are exposed so that it becomes possible readily to connect a web to them or to remove it therefrom.

What is claimed is:

1. A changeable sign for use in public vehicles, including a housing having an opening, separate spools therein, a web connected to and adapted to be wound on the spools, said web constituting the sole driving connection between the spools, a gear rotatable with one of the spools, a segmental gear movable into mesh with the spool gear to intermittently rotate the same, means for transmitting motion to the segmental gear from one of the wheels of the vehicle to rotate said segmental gear continuously, there being spaced signs on the web adapted to be exposed successively through the opening in the housing, the distances between the signs gradually increasing from one end of the web to the other thereby to compensate for variations in the diameter of the roll of web while being wound upon or unwound from one of the spools, the actuation of the gears being timed to successively expose the signs within the opening means for uncoupling the spool gear from the segmental gear, and adjustable tension means for holding the spools against free rotation.

2. A changeable sign for use in public vehicles, including a housing having an opening, separate spools therein, a web connected to and adapted to be wound on the spools, said web constituting the sole driving connection between the spools, a gear rotatable with one of the spools, a segmental gear movable into mesh with the spool gear to intermittently rotate the same, means for transmitting motion to the segmental gear from one of the wheels of a vehicle to rotate said segmental gear continuously, there being spaced signs on the web adapted to be ex-

posed successively through the opening in the housing, the distances between the signs gradually increasing from one end of the web to the other thereby to compensate for variations in the diameter of the roll of web 5 while being wound upon or unwound from one or the spools, the actuation of the gears being timed to successively expose the signs

within the opening, means for holding the spools against free rotation, and manually 10 operative means for rotating one of the spools to wind the web thereon when the gears are out of mesh.

In testimony that I claim the foregoing as my own, I have hereto affixed my signature.

JOSEPH D. SELF.
